LEGGING

Karl E. Jensen, Danville, Ill., assignor, by mesne assignments, to Ervin F. Kemp, Washington, D. C.

Application October 27, 1930. Serial No. 491,440

1 Claim. (Cl. 36—2)

The invention relates generally to leggings and more particularly to an industrial legging especially adapted for use by workmen in steel mills, foundries, etc., as a protection against flying particles of molten metal or other hazards.

An object of the invention is to provide a new and improved legging adapted to protect the leg and foot of the wearer and which may be very rapidly removed from a wearer's leg so that in an emergency, as when molten metal is splashed against the legging, the wearer may remove the legging before the metal has time to burn through the legging and injure him.

More specifically stated, it is an object of the invention to provide a legging in which a leg protecting covering is provided with quickly detachable means for holding the covering in place including a series of transversely extending apertures in one side of the covering and a hook-member in the form of a stud having a short lateral projection thereon carried by the other side of the covering, said hook member being relatively small to permit entrance thereof through an aperture in a straight line direction to effect an engagement with the aperture which is maintained by the tension of the covering about the wearer's leg and may be released by a relatively slight turning or pivotal movement of the hook member with respect to the aperture.

Another object of the invention is to provide a legging in which a leg protecting covering, formed from a single substantially regularly shaped piece of material adapted to extend about a wearer's leg, has quickly detachable means thereon adjacent the upper edge for securing and maintaining said covering in position and further embodies a pair of flexible members extending between spaced parts of the lower edge of the covering to properly shape portions of said covering to receive the wearer's heel and to cover or extend about the wearer's instep, said last mentioned portion having a flare thereon arranged to overlie and protect the front part of the wearer's foot.

Other objects and advantages will become apparent in the following description and from the accompanying drawing, in which:

Figure 1 is a side elevation of a legging embodying the features of the present invention. Figs. 2 and 3 are enlarged cross sectional views of the fastening means for the upper portion of the legging showing two relative positions of the parts.

Fig. 4 is an inside view of the legging in substantially extended condition.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claim.

With particular reference to the drawing, the present invention is presented in connection with a flexible leg protecting covering generally designated 10 which is adapted to encircle a wearer's leg and position the opposite sides thereof in overlapping relation. Usually, the protecting covering is formed of leather or a similar wear resisting or protective material, and the legging is so constructed that the edges or sides thereof meet on the outer side of the leg.

Since the present industrial legging is particularly adapted for use by workmen in industries in which the workmen continually handle hot articles or materials, it has been found that the ordinary type of close fitting legging becomes very uncomfortable to the wearer after it has been worn for a short space of time. The present invention overcomes this difficulty by providing means for securing and maintaining the leg protecting covering on a wearer's leg in such manner that free circulation of air throughout substantially the entire length of the legging is permitted. To this end, means are provided for securing the upper portion of the legging in a substantially close fitting or snug relationship to the wearer's leg, while other means are employed for maintaining the lower portion of the legging in spaced relation to the wearer's ankle and foot, and, at the same time, for disposing the legging in a protecting position relative to the parts from which it is spaced.

As may be seen in Figs. 1 and 4, the preferred means for holding the lower portion of the legging in place comprises the following construction: An elongated flexible member 11 is connected at one end to the flexible covering adjacent the lower edge and near one side thereof. The other end of the member is secured to an intermediate portion of the flexible covering near the lower edge thereof. The member is substantially shorter than the length of the portion of covering connected thereby so that said portion of covering is held in the form of a curl or fold generally indicated at 12. By properly predetermining the relative sizes and the dis-

position of the parts, this arrangement produces a pocket into which the wearer may insert the heel of a shoe with the member 11, of course, extending beneath the instep of the foot, in front of the heel (see Fig. 1).

Similarly, a second flexible member 13 extends between the opposite side of the legging from that to which the first flexible member 11 is secured, and an intermediate portion of the covering. The second member is likewise shorter than the length of the portion of covering connected thereby to form a fold indicated at 14 on the part of the legging which may be designated the front. However, the second member 13 is secured to the inner side of the covering and is preferably positioned upwardly of the covering a short distance from the lower edge thereof so that when the legging is in position on a wearer's leg, the second member extends across and engages the wearer's instep, as is clearly shown in Fig. 1.

In consequence of this construction, it will be evident that the portion 14 of the covering will be maintained in an outwardly extending position with respect to the wearer's leg, and at the same time will overlie and protectingly enclose the front portion of the wearer's leg and instep. A protecting flare 15, formed preferably of two appropriately shaped pieces of heavy leather or the like secured as by stitching to each other and to the lower front edge of the fold 14, extends forwardly of the legging to overlie and protect the front or toe portion of the wearer's foot. The flare, therefore, affords additional protection without hampering the free circulation of air permitted by the loose fit of the lower portion of the covering.

The construction of the lower portion of the legging includes a means for securing the meeting sides of the legging together in such manner that said sides may be quickly separated. A pocket 16 is provided along one side edge of the legging in any suitable manner as by sewing a separate strip of material along the side or by turning and stitching the side upon itself. This pocket receives an elongated strip of stiffening material, such as the metal bar 17. The lower end of the pocket 16 terminates a short distance from the lower edge of the covering and the stiffening bar extends outwardly beyond the pocket a short distance, as shown at 18 (Fig. 4).

The opposite side of the legging carries a vertically opening pocket 19 formed in any suitable manner, as by stitching a strip of leather to the side of the covering, which pocket is positioned to receive the lower end 18 of the bar 17. Insertion of the end of the bar into the pocket maintains the lower portion of the covering in position about the wearer's foot, which maintaining engagement may be instantly released by merely withdrawing the end of the bar from the pocket.

As has been mentioned, the upper portion of the legging fits snugly about the wearer's leg and in the present embodiment means are provided for holding the legging in this position, which means is capable of ready adjustment to any size and may also be instantly released. To this end, one side of the covering, which preferably is the side which passes about the rear portion of the wearer's leg, is provided with a plurality or series of spaced apertures 20 which extend transversely of the covering so as to be in a substantially horizontal plane when the covering is on the wearer's leg. These apertures are preferably reinforced

and defined in any suitable manner as by eyelets.

The other or overlapping side of the legging carries a means for engaging any of the apertures to secure the two sides together, which means is capable of being easily engaged with any of the apertures and may be quickly disengaged by a slight relative turning or pivotal movement. With particular reference to Figs. 2 and 3, a means of this character is illustrated in the nature of a hook member rigidly secured to the bar 17. The hook member in its preferred form comprises a short stud or pin 21 provided with a laterally extending projection 22 which is quite short and faces in the direction of the body of the legging. Thus, the structure presents a hook member which opens away from the vertical edge of the side to which it is secured. The relative sizes of the hook member and apertures are such that the hook member may pass coaxially through any aperture; or in other words may pass through an aperture in a straight line direction.

A finger piece 23 is secured to and extends upwardly from the side of the legging in which the apertures are located and a second finger piece 24 extends outwardly beyond the edge of the side of the legging on which the hook member is mounted. These finger pieces are for the convenience of the wearer in donning the legging. Thus, the wearer wishing to place the legging in position about his leg and foot, places his heel within the pocket or curl 12 with the flexible member 11 disposed in front of the heel of the wearer's shoe. The flexible covering is then passed about the leg and the projecting end 18 of the bar 17 is inserted in the pocket 19. This brings the flexible member 13 into engagement with the wearer's instep and disposes the front portion 14 of the legging and the flare 15 in loosely overlying protective relation to the front of the wearer's foot.

The wearer, by grasping the finger pieces 23 and 24, draws the overlapping sides of the covering in opposite directions until the desired degree of tension of the covering about the upper portion of the leg is obtained. A straight line movement of the hook member toward the leg causes said member to engage an underlying aperture 20 whereupon release of the finger piece 24 allows the tension of the covering about the leg to draw the hook member into holding engagement with the engaged aperture (see Fig. 2). In order to facilitate entry of the hook member into the aperture, the outer end of the stud 21 and the projection 22 taper sharply from the 130 projection to provide a rounded outer surface 25. This surface engages the margin of the aperture and insures the engagement of the parts during the straight line movement.

When the wearer wishes to remove the legging from his leg, he grasps the finger piece 24 with one hand and pulls slightly outwardly from and forwardly of his leg. The first turning or pivotal movement of the hook member suffices to release the short projection 22 from its engagement with the aperture (see Fig. 3), after which a slight continuation of the pull frees the stiffening member 17 from the pocket 19 to permit the wearer to step clear of the legging. It will be evident that this construction permits the legging to be very quickly removed from the wearer's leg in the case of emergency.

From the foregoing, it will be apparent that a novel legging has been provided which is comfortable, eliminates any restriction to the move-

ment of the wearer's foot and ankle, which affords complete protection to the leg and foot of the wearer, and may be quickly unfastened and removed from the wearer's leg.

5 I claim as my invention:

In a legging, the combination of a leg protecting covering adapted to encircle a wearer's leg with the sides of the covering in overlapping relation, and means for detachably securing the sides together including a transversely extending series of apertures through one of the legging sides, and a relatively short stud on the other of said sides adapted to be extended through

any one of said apertures, said stud having a lateral projection thereon facing transversely toward the front of the legging, the relative sizes of said stud and projection and apertures being such that the stud may enter the apertures coaxially to effect an engagement of the projection with an aperture, which engagement is maintained by the tension of the covering about the wearer's leg and is instantly releasable by a relatively short pivotal movement of the stud caused by an outward and forward pull on the covering side to which the stud is attached.
